ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

MECHANISM FOR LOCKING BATTERIES OF DOORS.

1,133,659.

Specification of Letters Patent. Patented Mar. 30, 1915.

Application filed December 28, 1912. Serial No. 738,672.

To all whom it may concern:

Be it known that I, ALBERT A. PAGE, a citizen of the United States, residing at East Haven, county of New Haven, and State of Connecticut, have invented certain new and useful Improvements in Mechanism for Locking Batteries of Doors, of which the following is a full, clear, and exact description.

10 This invention relates to mechanism for locking batteries of doors such as exit doors of school houses, theaters and similar buildings.

15 My improvements are particularly applicable to mechanism for simultaneously locking two or more pairs of swinging doors arranged in a row, but they are also applicable to mechanism for locking three swinging doors, and certain features of the invention 20 may be found useful in locking a single door or the doors of a single pair.

The primary objects of my invention are to provide a simple, efficient and conveniently operable mechanism for bolting one 25 or more doors, and to furnish a construction in which the locking mechanism for both doors of a pair, or for a single door, is connected in a simple but effective manner with similar locking mechanism of another door 30 or doors, so that all of the doors of the battery or series may be locked and unlocked simultaneously, with the expenditure of a minimum amount of energy on the part of the operator.

35 To these and other ends, the invention consists in the novel features and combinations of parts to be hereinafter described and claimed.

In the accompanying drawings, Figure 1 40 is an elevation of a battery of four doors equipped with my improvements, looking from the outside of the building. Fig. 2 is a horizontal section of Fig. 1, Fig. 3 is an enlarged view from the inside, with parts 45 broken away, showing portions of the two doors at the right hand end of Fig. 2, and their associated locking mechanism, Fig. 4 shows on a still larger scale the locking mechanism illustrated in Fig. 3, looking 50 from the outside, the outside casing or covering panel being omitted, and the swinging double bolt being in its locking position, Fig. 5 is a section on line 5—5 of Fig. 4, Fig. 6 is a view similar to Fig. 4 but 55 showing the swinging double bolt in its in-

operative position. Fig. 7 is a section on line 7—7 of Fig. 4, Fig. 8 is a section on line 8—8 of Fig. 6, Fig. 9 is a section on line 9—9 of Fig. 6, Fig. 10 is an enlarged section on line 10—10 of Fig. 1, Fig. 11 is an enlarged section on line 11—11 of Fig. 1, Fig. 12 is a detail of one of the fronts, Fig. 13 is a detail of one of the strikes, and Fig. 14 is a detail of the key.

In the drawings, I have shown my improvements applied to a battery of four swinging doors arranged in two pairs. A single bolting mechanism is associated with the mullion between the doors of one pair, in order to lock to the mullion the adjacent free edges of said doors. This mechanism for locking the doors of a single pair is connected by means of suitable transmission mechanism to a similar locking mechanism associated with the second pair of doors, and at least one of the locking mechanisms is operable by means of a suitable key, so that all four doors may be locked and unlocked simultaneously. However, it will be understood from the following description 80 that the improvements are applicable to more than two pairs of doors and that one or more of the bolting mechanisms employed may lock and unlock a single door 85

In Figs. 1 and 2 of the drawings, I have indicated the four doors above mentioned as A, B, C and D respectively. The doors A, B swing toward each other and constitute one pair, and the doors C, D swing toward each other and constitute the other pair. The adjacent or free edges of the doors A, B are separated by a mullion E, and a similar mullion F is associated with the doors C, D. Bolting mechanism G is associated with the mullion E to lock the doors A, B, and said bolting mechanism is connected by means of suitable transmission mechanism (denoted generally by reference character H) with similar bolting mechanism I associated with the mullion F for locking the doors C, D. The mullions E, F and the upper part of the door frame are preferably made in the form of hollow casings so that the bolting devices G, I and the transmission mechanism H may be housed therein and concealed from view. All of the doors are hinged to swing outward, as usual in school houses, theaters and similar buildings, so that when the locking mechanism 105 110

has once been released or placed in the inoperative position by the janitor or other attendant, all of the doors will be free to swing outward. The advantages of this arrangement in the event of a panic resulting from fire or other cause are well understood. The simultaneous locking and unlocking of the doors of the battery may be effected by manipulation of a key J insertible into the mullion F to coöperate with the bolting device I. The entire locking mechanism should be inaccessible from the outside of the building and the key J should be insertible into the mullion F from the inside only, so that no particular safeguards against picking are necessary.

Referring now to the particular construction of the bolting mechanisms or devices G, I, it will be sufficient to describe one of these devices, only, as both of them are constructed and mounted in the same manner. The device I, illustrated in Figs. 3 to 9 inclusive, comprises a base plate 20 which serves as a mounting for a double bolt 21 coöperating with both doors C, D. Referring particularly to Figs. 4, 5 and 7, it will be noted that the plate 20 is attached by means of screws 22 to a stud 23 arranged within the mullion F. The stud 23 is interposed between jambs 24 which constitute the side walls of the hollow mullion and the inner and outer walls of the mullion are constituted by inside and outside panels 25 and 26 respectively applied to the jambs in the manner shown in Figs. 7 and 8. The double bolt 21 is illustrated as of the lever type having a bearing 27 in the plate 20 and provided with oppositely extending arms or blades 28 and 29 respectively, coöperating with the respective doors C, D. In other words the double bolt is mounted to oscillate in a vertical plane in a bearing intermediate of its ends, afforded by the plate 20. The arm 29 of the bolt operates in a slot 30 extending vertically in one of the jambs 24, and the arm 28 operates in a similar slot 30 in the other jamb. Suitable metal strikes 31 (Fig. 13) are mortised in the slotted portions of the jambs, and these strikes coöperate with metal fronts 32 mortised in the edges of the doors C, D at the mouth portions of the mortises or slots 33 in which the extremities of the bolt arms 28, 29 are adapted to be received, as shown in Fig. 7.

Referring particularly to Fig. 6, it will be noted that when the bolting mechanism is in its inoperative position, the arms 28 and 29 of the double bolt will be vertically directed, parallel to the plate 20. As the bolt is swung on its axis to lock the doors C, D, as shown in Fig. 4, the upper arm will be swung downward into one of the slotted fronts, and the lower arm will be swung upward into the front of the other door until both arms are approximately

horizontal. Inasmuch as it is expedient to slot or mortise the doors and mullions to a minimum extent, and to make the fronts and strikes as small as possible, the door mortise, front, mullion slot, and strike co-operating with one of the bolt arms will preferably be somewhat above the corresponding parts coöperating with the other bolt arm, as shown. The bolt 21 is actuated by means of the key J previously mentioned, which may comprise a shank 34 having a T-head 35. The shank 34 is provided with a squared extremity 36 adapted to engage a square hole 37 cut in the axial portion of the bolt. Access to the bolt hole 37 is permitted by way of a bore or auger hole 38 in the stud 23 communicating with a hole 39 in the panel 25 finished off by a suitable escutcheon 40. As the key J is inserted through the escutcheon 40, hole 39 and bore 38, its squared end 36 will engage the square hole in the bolt so that as the key is turned the bolt may be swung or oscillated to engage the bolt arms 28 and 29 with or disengage them from the slotted fronts of the respective doors. In this manner when the mechanism is in the inoperative position shown in Fig. 6 a quarter turn of the key in one direction will cause the bolt to be moved into the locking position shown in Fig. 4, and the doors may be released by giving the key a quarter turn in a reverse direction.

The transmission mechanism H connecting the bolting mechanism I with the bolting mechanism G may take the form of gearing comprising an upright shaft 41 having bearings in lugs 42 carried by the plate 20 of the mechanism I, above and below respectively the bolt 21. Intermediate the lugs 42 the shaft 41 has fixed thereto a bevel gear 43 meshing with a bevel gear 44 which may be formed integral with the intermediate bearing or hub of the bolt, as shown. The gears 43 and 44 are provided with an equal number of teeth so that as the bolt is swung on its axis the shaft 41 will be oscillated in its bearings to a corresponding extent. The shaft 41 extends to the top of the mullion F where it has another bearing in an L-shaped plate 45 (Fig. 3) located partly within the mullion F and partly within a hollow horizontal casing or lintel 46 extending across the tops of the doors B, C. At the upper end of the shaft 41 is fixed a bevel gear 47 (Figs. 3 and 10) meshing with a similar gear 48 on a horizontal shaft 49 journaled at one end in the plate 45 and at the other end in a similar plate 45 (only generally shown in Fig. 1) located partly within the casing 46 and partly within the mullion E. The locking mechanism G has associated therewith a shaft 41 similar to that previously described, and the upper horizontal shaft 49 is connected with both of the shafts 41 in the same manner. The

bevel gears of the intermeshing pairs are all of the same size and hence it will be understood that as the shaft 41 associated with the doors C, D is rotated in one or the other

5 direction, by the actuation of the bolt, the connection between said shaft and the shaft 41 associated with the doors A, B will cause the latter shaft to be simultaneously rotated to a corresponding extent, whereby the 10 bolts of both locking mechanisms will be simultaneously actuated to lock or release all of the doors. Both bolts will be moved simultaneously in the same direction and to the same extent. It is not necessary in all 15 aspects of the invention that the two or more locking devices be interconnected by means of gearing, as any other equivalent form of transmission mechanism may be employed.

20 The improved mechanism has been found of special advantage when applied to the exit doors of school houses. At night, when the building is to be locked up, all of the doors may be locked simultaneously by a 25 single manipulation of the key from the inside. In order to lock all of the doors, it is simply necessary to see that they are completely shut before the key is used for throwing the bolts, and door closers may 30 normally hold the doors closed if desired. The locking mechanism is absolutely inaccessible from the exterior of the building, and no particular safeguards against picking the locking mechanism are necessary.

35 When the school house is opened for the daily session all of the doors may be released simultaneously by a single operation of the key, and during school hours every door of the series will be ready to swing outward under the slightest push, so that free 40 exit can be had in case of a panic.

The foregoing description is necessarily a detailed one in so far as it concerns the particular embodiment of my invention selected for illustration and description, and I have not attempted to describe the various modifications of the construction which may be adopted within the scope of the claims. One of the most obvious modifications is the 50 omission of one of the locking arms of the double bolt, to make it a single bolt, in case one or more of the bolting devices is to lock a single door only.

What I claim is:

55 1. The combination of two doors mounted to swing toward each other, a hollow mullion interposed between said doors and having slots in the respective side walls, one of said slots located higher than the other, a plate 60 mounted within said mullion, a swinging bolt pivoted on said plate and having arms operating in the respective slots of the mullion, and adapted to project through said slots when the bolt is turned into a definite 65 position, said doors being provided at their

edges with recesses to engage the terminals of the respective arms, and a key insertible into said mullion to actuate said bolt; substantially as described.

2. The combination of two doors mounted 70 to swing toward each other, a hollow mullion interposed between said doors, and comprising side members affording jambs for the doors, inner and outer panel members, and an interior stud member, the side members 75 being provided with vertical slots, a plate within the mullion attached to said stud member, a double swinging bolt mounted on said plate and operating in said slots and adapted to engage recesses in the respective doors, and a key insertible into the mullion to actuate said bolt; substantially as described.

3. The combination of two doors mounted 80 to swing toward each other, a hollow mullion interposed between said doors, and comprising side members affording jambs for the respective doors, inside and outside panels, and an interior stud member, the side members 85 of said mullion being provided with vertical slots, one located above the other, a plate secured to said stud member within said mullion, a vertically swinging bolt pivoted on said plate and having arms 90 operating in the respective slots of the mullion, and adapted to engage recesses in the edges of the respective doors, and a key to engage and turn said bolt, one of said panels having an opening through which said key is insertible; substantially as described. 100

4. The combination of two doors mounted 105 to swing toward each other, a hollow mullion interposed between said doors, a double swinging bolt mounted in said hollow mullion and arranged to lock both doors simultaneously, a key insertible into said mullion to actuate said bolt, a second pair of doors mounted to swing toward each other, a hollow mullion interposed between the doors of said second pair, a second double swinging 110 bolt mounted within said second mullion and arranged to lock both doors of the second pair simultaneously, and transmission mechanism connecting said bolts whereby both may be actuated by a single movement 115 of said key; substantially as described.

5. In a battery of fire exit doors, the combination of a pair of doors mounted to swing toward each other, a mullion interposed between said doors, a locking device 120 for said doors supported on said mullion, a third door, a mullion associated with the third door, a locking device for said third door mounted on the last-named mullion, means for operating one of said locking devices, and means interconnecting said locking devices so that both are operated together; substantially as described. 125

6. In a battery of fire exit doors, the combination of a frame, a pair of doors in said 130

frame mounted to swing toward each other, a mullion interposed between said doors, a third door in the frame, a mullion associated with said third door, said frame including a hollow portion extending above said doors, locking devices mounted within the first and second mullions respectively, and transmission mechanism for interconnecting said locking devices, located in part in said mullions and in part in the hollow portion of the frame above the doors; substantially as described.

7. In a battery of fire exit doors, the combination of a frame having a hollow upper portion, two doors in said frame mounted to swing toward and away from each other, means affording jambs for the respective doors, locking devices for the doors associated with the respective jambs, means for operating one of said locking devices, and transmission mechanism between said locking devices, located in part in the hollow portion of the frame above the doors; substantially as described.

8. In a battery of fire exit doors, the combination of a frame having two hollow mullions, and a hollow lintel portion connecting said mullions, one or more doors having a jamb on each mullion, a door-locking device mounted within each mullion, means for operating one of said door-locking devices, and transmission mechanism interconnecting said locking devices and located in said hollow mullions and in said hollow lintel portion of the frame; substantially as described.

9. In a battery of fire exit doors, the combination of a frame having a hollow lintel portion, hollow mullions in said frame connected with said hollow lintel portion, door-locking devices mounted within the respective mullions, a shaft in the hollow lintel portion of the frame between said mullions, means connecting said shaft with the respective locking devices so that all of said locking devices are operated simultaneously, means for operating said locking devices, and doors in the frame coöperating with the respective mullions and locking devices; substantially as described.

10. In a battery of fire exit doors, the combination of a frame having a hollow lintel portion, hollow mullions in said

frame, each composed of inside and outside panels and slotted side members, double swinging bolts mounted in the respective mullions and operating in the slots thereof, one of said bolts being adapted for engagement by a key, and one of the panels of the corresponding mullion being provided with a suitable keyhole, a pair of doors in the frame coöperating with each mullion and the double bolt thereof, and transmission mechanism interconnecting said bolts, and located in part in said hollow mullions and in part in said hollow lintel portion of the frame; substantially as described.

11. The combination of a pair of doors, a mullion interposed between them, a third door, a mullion associated with said third door, and interconnected locking mechanisms associated with the respective mullions; substantially as described.

12. The combination of a pair of doors, a mullion interposed between them, a third door, a mullion associated with said third door, a locking device on the first mullion to lock said pair of doors, a locking device on the second mullion to lock the other door, and transmission mechanism between said locking devices whereby they are actuated simultaneously, substantially as described.

13. The combination of a pair of swinging doors, a mullion interposed between them, a third swinging door, a mullion associated with said third door, pivoted locking members carried by the respective mullions, one of said members being operable to lock said pair of doors, and the other being operable to lock the third door, and gearing connecting said members; substantially as described.

14. The combination of a plurality of pairs of swinging doors, a mullion interposed between the doors of each pair, locking devices carried by each mullion to lock the corresponding pair of doors, and means connecting said locking devices so that they are operated simultaneously; substantially as described.

In witness whereof, I have hereunto set my hand on the 21st day of December, 1912.

ALBERT A. PAGE.
